His Attorney

UNITED STATES PATENT OFFICE.

JOSEPH A. PARRELLA, OF WASHINGTON, DISTRICT OF COLUMBIA.

RESILIENT HEEL.

Application filed November 17, 1921. Serial No. 515,850.

To all whom it may concern:

Be it known that I, JOSEPH A. PARRELLA, a citizen of the United States, residing at Washington, in the District of Columbia, have invented certain new and useful Improvements in Resilient Heels, of which the following is a specification.

This invention relates to an improvement in resilient heels, and has particular reference to that type of heel or lift which may be attached to the shoe without the use of cement, yet retains all of the advantages derived by the use of such cement.

An object of the invention is to provide a heel lift which is so shaped, that when same is nailed on the shoe will bind tightly against said shoe, to thereby exclude all foreign matter such as water etc. As is well known water getting between the leather heel and the rubber heel causes the nails to rust and thereby loosens the heel.

A further object of the invention is to provide such a heel which embodies in its construction a special form of washer, which when the heel is attached to the shoe, will be forced into a reverse bend, such action in turn forcing a section of the upper surface of the heel into contact with the leather heel.

A further object of the invention is to provide a heel of the above mentioned character which is provided with a groove in its upper surface, which conforms to the line of washers and nails, such groove acting as a suction cup for additionally holding the heel against the shoe when the same is applied.

A further object of the invention is to provide such a heel which embodies all of the advantages of the heels now in use, is extremely simple in construction, strong, durable and highly convenient in use.

Other important objects and advantages of the invention will be apparent during the course of the following description.

Referring to the drawings, Figure 1 is a perspective view of a heel constructed in accordance with the invention.

Figure 2 is a plan view thereof.

Figure 3 is a front edge view, a part being shown in section, and before the heel has been nailed up.

Figure 4 is a front edge elevation of the heel after same has been nailed to the shoe.

Figure 5 is a transverse sectional view through the heel showing the same nailed up, and,

Figure 6 is a perspective view of the washer associated with the heel.

In the drawings wherein like numerals are employed to designate like parts throughout, the numeral 10 designates the heel as a whole, having a concave upper surface 11 and a convex lower surface 12. Formed a suitable distance from the edge of the heel and in the upper surface, is an arcuate groove 13. This groove is so curved as to conform to the line of nails employed to nail the heel upon the shoe. A recess 14 is formed in the heel near the front edge of the upper surface, and in a position to overlie the point at which the center nail will be placed. It will be observed that neither the groove nor the recess communicate with the outer edges of the heel. The ends of the groove are spaced a suitable distance from the front edge of the heel, so that when the heel is trimmed on the shoe, the groove will not be cut into.

Molded into the heel at the time of manufacture, are a plurality of washers 15, which washers are formed cup-shaped and are provided with holes 16 for the reception of nails 17 employed in attaching the heel. Before the heel is applied, the washers lie in a position as illustrated in Figure 3, and are cupped downwardly. When the heel is nailed up, the heads of the nails will engage the lower surface of the washers, as shown. The usual nail set is employed to set the nails up tight and will force said washers to partake of a cup shape in the opposite direction. It will be obvious that when such action takes place, the rubber adjacent the tops of the washers will be firmly pressed against the heel of the shoe. As shown in Figure 5, when the heel is attached the washers will force the central part of the groove 13 to bind against the heel. This leaves a slight space which acts as a suction groove to further assist in holding the heel to the shoe, and to further prevent foreign matter from entering between the shoe and the heel. The purpose of providing the recess 14 is to give an additional binding point at the front of the heel.

In operation, when it is desired to apply

2 a heel to a shoe, such heel is positioned as illustrated in Figure 3. The nails are then driven in as usual, and forced up tight so that the heel will lie upon the shoe as illustrated in Figure 5. The purpose in forming the heel concave, is to give it an additional binding force. The washer may be formed of any metal sufficiently soft to allow of bending. If desired, same may be formed 5 of flexible or spring material, but this is unnecessary to the proper operation of the invention. To insure of the proper bending of the washers, they are made sufficiently 10 large to overlie the edges of the groove 13, so that when the nails are set, the washers having a solid bearing of rubber at their 15 edges will be held against movement, while the central portions thereof will move upwardly due to the giving of the material of 20 the groove.

It will be obvious from the foregoing, that a heel has been provided which will be highly successful in use, and one that has very slight chance of becoming loose. To those 25 familiar with rubber heels, the value of such an invention will be apparent. It is an extreme nuisance to have a rubber heel come loose on the shoe, and this is many times due to the fact that the washer pulls through the 30 rubber. It is the common practice today to apply heels without the use of cement, and it was with this purpose in mind, that applicant 35 has provided a heel which will be held firmly upon the shoe without the use of such cement.

It is to be understood that the form of the invention herewith shown and described is to be taken as the preferred example thereof, but it is to be understood that various 40 changes in the shape, size and arrangement of parts may be resorted to without departing from the spirit of the invention or the scope of the subjoined claims.

Having described my invention, what I 45 claim is:—

1. A heel lift of the character described of concavo-convex formation and formed of resilient material, said lift provided with an 50 arcuate groove in its concave upper surface extending along its back and sides and terminating short of the front edge, a plurality

of nail holes being formed in the lower face of the lift and in alignment with the said groove, concavo-convex washers embedded in the material of the lift and in alignment with the said nail holes and said groove, the concave face of said washers lying adjacent the concave upper surface of the lift, said washers being of such material and thickness as to allow them to be inverted by the securing nails so as to force the material of the groove to bind tightly against the heel, a recess formed in the upper face of said lift adjacent the front edge and spaced therefrom, a nail hole being formed in the lower face of the lift and in alignment with the recess and a washer of concavo-convex formation embedded in the material of the lift and in alignment with the recess and the last named nail hole, said washer when forced upward by the securing nail binding the material of the recess firmly against the heel. 55 60 65 70 75

2. A heel lift formed of resilient material, and provided with an arcuate groove in its upper surface extending along its back and sides and terminating short of the front edge, a plurality of nail holes being formed in the lower face of the lift and in alignment with the said groove, concavo-convex washers embedded in the material of the lift, and in alignment with said nail holes and said groove, the concave face of said washers lying adjacent the upper surface of the lift, said washers being of such material and thickness as to allow them to be inverted by the securing nails so as to force the material of the groove to bind tightly against the heel, a recess formed in the upper face of the lift adjacent the front edge and spaced therefrom, a nail hole being formed in the lower face of the lift and in alignment with the said recess and a washer or concavo-convex formation embedded in the material of the lift and in alignment with the recess and the last named nail hole, said washer when forced upward by the securing nail, binding the material of the recess firmly against the heel. 80 85 90 95 100

In testimony whereof I affix my signature.

JOSEPH A. PARREILLA.
